UNITED STATES PATENT OFFICE.

WALTER SCOTT FINNELL, OF BROOKLYN, NEW YORK.

MOP-TRUCK.

1,236,156.

Specification of Letters Patent. Patented Aug. 7, 1917.

Application filed April 12, 1916. Serial No. 90,560.

To all whom it may concern:

Be it known that I, WALTER S. FINNELL, a citizen of the United States, residing at Brooklyn, in the State of New York, have 5 invented certain new and useful Improvements in Mop-Trucks, of which the following is a specification.

This invention relates to a mop truck for use in mopping floors of any kind. 10 The object of the invention is to provide a water-carrier comprising two compartments or two tanks, one for clean water and the other for water that has been mopped from the floor; the capacity of each 15 of these compartments may vary from ten to twenty-five gallons, and the two together are mounted on wheels to enable them to be readily moved about over the floors of hotels, railway stations, large stores, banks 20 and other places having a large area of floor surfaces, which require frequent scrubbing.

The invention is illustrated in the accompanying drawing, in which,—

Figure 1, is a perspective view of the mop 25 truck.

Fig. 2, is a longitudinal vertical section on a straight line through the two water-compartments.

Fig. 3, is a vertical cross-section taken 30 through one of the compartments, in this instance through the dirty-water compartment, on the broken line 3—3.

Referring to the drawing the construction 35 consists of two tanks which are of about the same size and are placed side by side both being seated in a suitable frame 4, which holds both tanks in a fixed position.

The numeral 5, designates the clean-water tank, and 6, the dirty-water tank. In the 40 present instance the two tanks are shown to be rectangular in shape, but it is obvious they may have other shapes such as that of upright cylinders. The tanks require to be constructed water-tight, and the bottom 7, 45 of each tank is preferably inclined, as seen in Fig. 2, and at the side where the bottom is lowest the tank is provided with a spigot 8, for use when it is desired to draw off water.

The truck structure, in the present instance, has three wheels; two of the wheels 9, are on one axle 10, and the third wheel 11, has a vertical shank 12, that turns in a vertical tubular bearing 13, like an ordinary 55 castor roller.

The frame 4, supports the two tanks and is made of bar-iron which in cross-section is right-angled, as shown in Figs. 2 and 3. This frame is supported above the wheels by three V-shaped studs—one such stud 14, 60 being connected with said tubular bearing 13, at the castor wheel, and a similar V-stud 14, on the axle 10, and projecting above each of the two wheels. The water tanks are seated on the flat horizontal side of the 65 angle-bars of said frame 4, while the flat vertical side of said angle-bar 4, projects up and contacts with the sides of the tanks 5 and 6. It will be understood the bottoms of the two tanks set down into the up-projecting sides of said rectangular frame 4, and the latter holds the two tanks from lateral movement.

The adjoining walls 15, of the two tanks are separated by a vertical space 16; a channel bar 17, extends horizontally across at the bottom of said space and between said two adjoining walls, and the ends of this bottom cross-bar take under the two opposite right-angled bars of the frame 4, as shown 80 in Fig. 3. A second channel bar 18, extends across at the top of said space 16 and closes the latter, and the ends of this top cross-bar take over the two opposite longitudinal right-angled bars, of the top rectangular frame 19. Two vertical rods 20, have position in the said space 16, that separates the adjoining walls 15, of the two tanks, and these rods connect the bottom cross-bar 17, with the top cross-bar 18, and 85 thereby the lower frame 4, and the upper frame 19, are firmly bound together and said two frames hold the two tanks 5 and 6, to 90 their position.

The rods 20, and two bars 17, 18, may be 95 differently arranged.

The dirty-water tank 6, is provided on two opposite walls interiorly with a cross cleat 21, positioned a short distance below the top rim of the tank, and these two cleats 100 support a perforated strainer or shield 22. The position of strainer 22, forms in the top of the dirty-water tank, 6, above the strainer a vacant space where a mop may be kept when it is not in use. When a mop, by a 105 back and forward movement, has been drawn over a wet floor, it is saturated with dirty-water that has been absorbed. The purpose of this strainer or shield 22, is to prevent the mop, when charged with dirty 110

water taken up from the floor, from being dipped into the dirty-water can, but allowing said mop to be first squeezed dry over the strainer, and then dipped into the clean-water tank. By this construction the mop charged with dirty-water wiped from the floor may be held over the open top of tank 6, while the operator squeezes from the mop the dirty water onto the strainer or shield 22, which latter will prevent the mop from being dipped into the tank; this squeezing may be done by hand or by using an ordinary roller wringer.

When the dirty water has been exhausted from the mop, the operator may dip the dry mop into the clean water of the other tank 5, and then the mop with clean water may be again applied to the floor, and the operation repeated.

By means of this mop truck clean water held in one tank whose top may be kept covered, can be readily carried about to any position, and the mop once saturated with dirty-water from the floor can be wrung while held over the open screened top of the dirty-water tank; this operation prevents the clean water in tank 5, from being seriously polluted, and insures that the dirty water mopped from the floor will be confined to the one tank, 6.

This operation of mopping the dirty water from a floor that has been scrubbed, is

greatly facilitated by using the two tanks of which one has a dirty-water strainer, 22.

The truck can be easily pushed about in any direction. The supply of clean water carried in one tank, and the dirty water taken from the floor carried in the other tank.

The dirty-water in tank 6, is to be drawn off through spigot 8, and received into a bucket to be placed under said spigot.

Having described my invention what I claim is,—

A mop-truck comprising a rectangular base frame; two rectangular tanks seated side by side upon said base frame with the walls of said tanks that adjoin separated from each other by a narrow vertical space; a rectangular frame attached to the tops of said two tanks; a bottom cross-bar extending through said vertical space with ends engaging opposite bars of said base-frame; a top cross-bar extending through said space with ends engaging the top frame, and vertical rods positioned in said space and connecting with both said bottom and top cross-bars.

In testimony whereof I affix my signature in the presence of two witnesses.

WALTER SCOTT FINNELL.
